UNITED STATES PATENT OFFICE.

BENJAMIN F. BELLows, OF NEVADA, MISSOURI, ASSIGNOR OF ONE-THIRD TO
MARTHA E. TOSTON, OF BRICELAND, CALIFORNIA.

WINDMILL.

1,363,174.

Specification of Letters Patent. Patented Dec. 21, 1920.

Application filed May 7, 1919. Serial No. 295,327.

To all whom it may concern:

Be it known that I, BENJAMIN F. BELLows, a citizen of the United States, residing at Nevada, in the county of Vernon and 5 State of Missouri, have invented new and useful Improvements in Windmills, of which the following is a specification.

The object of the invention is to provide a simple, relatively inexpensive and efficient 10 wind-mill designed for pumping and for furnishing power for driving machinery, the parts being so related as to minimize friction and secure the maximum strength and durability while enabling the operator 15 to obtain ready access to the various parts for the purpose of lubrication and adjustment.

Further objects and advantages of the invention will appear hereinafter, it being 20 understood that changes in form, proportion and details may be resorted to, within the scope of the claims, without departing from the spirit of the invention.

In the drawings:—

25 Figure 1 is a side view of a wind-mill constructed in accordance with the invention.

Fig. 2 is a plan view of the same.

Fig. 3 is a sectional view taken through 30 the wing controlling mechanism.

Fig. 4 is a detail perspective view showing the means by which vanes are brought back to operating position after having been thrown to feathering position.

35 Fig. 5 is a detail perspective view of the inner end of one of the wing shafts showing mounted thereon the holding cam and the tappet.

The frame work or tower 10, which may 40 be either of wood or metal is preferably mounted upon a concrete or cement foundation 11, so as to give the requisite solidity to the structure, and mounted therein is a tubular power shaft 12 carrying a drive gear 13 meshing for example with a pinion 14 on a driven or service shaft 15 from which motion may be communicated for the operation 45 of a pump or other machinery.

Attached to the drive shaft is a wind 50 wheel spider 16 of which the arms 17 are provided with inner and outer seats 18 and

19 preferably having lateral flanges 20 and 21.

Mounted in the seats are the bases 22 of pedestals 23 in which are formed bearings 55 for the shafts 24 of the blades 25 which are of the feathering type and are, as shown, designed to be reversed in position so as to present their broad surfaces or sides to the wind on the forwardly moving side of the 60 wheel, and their edges on the opposite or returning side thereof. The spider is mounted upon a bearing plate or table 26 with suitable interposed ball or roller anti-friction devices, and the lower end of the shaft may 65 be similarly stepped in anti-friction bearing in the foundation.

Mounted within the tubular drive shaft is a stem 27, preferably tubular and carrying the vane 28, said stem having anti-friction bearing in the bore of the drive shaft as by providing it with collars 29 and 30 which are supported by shoulders 31 and 32 with interposed anti-friction balls 33.

The vane stem carries a disk 34 having a 75 depending flange 35 for engagement with holding cams 36 on the blade shafts, and the vane stem also carries tappet arms 37 and 38 for engagement successively by tappets 39 on said blade shafts whereby as the wheel 80 revolves under the influence of the air striking the blades, the latter are alternately moved from one position to the other in which they are held respectively by the engagement of the holding cams which are in 85 operative relation with the flange of the disk 34.

What is claimed is:—

1. A wind mill having a vertical tubular drive shaft, a vane having a stem telescopically mounted within the bore of the drive shaft, a horizontal wind wheel having a spider carried by the drive shaft and feathering blades provided with shafts mounted upon the spider, a disk carried by the vane 90 stem and provided with a cam flange, cams carried by the blade shafts for blade holding contact with said flange, the extent of the latter being approximately equal to one-half the orbital path of the wheel, and tappet arms on the vane stem for reversing the 95 position of the blade shafts.

2. A wind mill having a vertical tubular drive shaft, a vane having a stem telescopically mounted upon the drive shaft, a horizontal wind wheel having a spider carried by the drive shaft and feathering blades provided with shafts mounted upon the spider, tappet arms extending radially from the blade shafts, tappet arms extending

from the vane stem respectively in the paths of the tappet arms on the blade shafts, and means for holding the wheel shafts in their adjusted positions in the intervals between engagements of said tappet arms.

In testimony whereof I affix my signature.

BENJAMIN F. BELLows.
